[57] CLAIM

The ornamental design for a water heated container for
temperature retention and support of food service pans,
as shown and described.

DESCRIPTION

FIG. 1 is a top plan view of a water heated container for
temperature retention and support of food service pans
showing our new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a right front and top perspective view thereof;

and,

FIG. 8 is a bottom and rear perspective view thereof.

FIG. 1

FIG. 2

FIG. 1.

FIG. 2.

FIG. 3.

FIG. 4.
